UNITED STATES PATENT OFFICE.

EDWARD C. GILLE, OF STAMPEDE, NORTH DAKOTA.

AGRICULTURAL IMPLEMENT.

1,211,135.

Specification of Letters Patent.

Patented Jan. 2, 1917.

Application filed July 29, 1915. Serial No. 42,526.

To all whom it may concern:

Be it known that I, EDWARD C. GILLE, a citizen of the United States, residing at Stampede, in the county of Burke and State 5 of North Dakota, have invented certain new and useful Improvements in Agricultural Implements, of which the following is a specification.

My invention relates to improvements in 10 agricultural implements, and refers particularly to an attachment for gang plows or cultivators, the object being the provision of a simple, inexpensive and durable attachment placed upon the hanger and bearing of 15 the rear supporting wheel, to prevent weeds or other growth from becoming entangled with the wheel or hanger.

Another object of my invention is the provision of an attachment of the character and 20 for the purpose stated which can be easily applied to implements in use or at the time of their manufacture, which will be reliable and efficient in operation, which will not interfere with the action of the hanger or 25 wheel and which will be practical in every particular.

With these objects in view my invention consists of a yielding or spring arm connected to the hanger and hub of the wheel to act 30 as a guard or fender to prevent weeds, brush or growth from entanglement with the hanger or wheel.

The invention further consists of an attachment of the character and for the purpose stated embodying novel features of construction and arrangement of parts for service substantially as shown, described and 35 claimed.

In order that the details of construction 40 and operation of my invention may be fully understood and its many advantages be appreciated I have shown in the accompanying drawing an attachment embodying my invention.

45 Figure 1 represents a side elevation of the wheel and portion of the hanger with my attachment applied. Fig. 2 represents a rear end elevation thereof, and Fig. 3 represents a detail view showing the manner of clamp-

ing and securing my attachment to the 50 hanger.

It will be understood that my device may be used upon any implement where it would operate practically, and in the drawing I have shown the attachment in connection 55 with the hanger A, such as used upon riding gang plows, said hanger being formed with the axle B, for the hub C, of the wheel D. My attachment consists of the curved rearwardly extending arm E, formed at its upper portion with the spring coil F, which encircles the hub and is formed with the loop G, a portion G', of which passes through an opening G², in the hanger and terminates in a vertical portion H, which is 60 arranged against the hanger and clamped thereon by means of the band clamp J.

The operation of my attachment will be readily apparent and I would state, that the 65 spring arm rests upon the ground and moves 70 with the hanger and wheel, and acts as a fender or guard to engage the weeds, brush or growth to hold same away and prevent entanglement with the wheel or hanger, the attachment by reason of its spring action 75 accommodating itself to the required service.

It is evident that I provide an attachment 80 which is of great utility and possesses much merit and which can be produced at such a figure as to make its use highly desirable and necessary.

I claim:

In combination with the hanger and ground wheel of an agricultural implement, a fender connected to said hanger and wheel 85 to prevent growth from becoming entangled therewith, said fender consisting of a ground engaging arm, a spring coil, and a terminal passing through an opening in the hanger, said terminal being clamped to said 90 hanger.

In testimony whereof I affix my signature in the presence of two witnesses.

EDWARD C. GILLE.
